241,832

COMBINED SERVICE STATION AUXILIARY BUILDING AND CANOPY

Elliott F. Noyes, New Canaan, Conn., assignor to
Mobil Oil Corporation

Filed June 18, 1974, Ser. No. 477,869

Term of patent 14 years

Int. Cl. D25—03

U.S. Cl. D25—34

FIGURE II

FIGURE III

FIGURE IV

FIGURE I

FIGURE V

FIG. I is a front elevation view of a combined service station auxiliary building and canopy of my new design.

FIG. II is the entry elevation view or right side of the building of FIG. I.

FIG. III is the left side elevation view of the building of FIG. I.

FIG. IV is the rear elevation view of the building of FIG. I.

FIG. V is the sectional view of the combined service station auxiliary building and canopy shown in FIGS. I, II, III and IV taken on line V—V of FIG. I.

I claim:

The ornamental design for a combined service station auxiliary building and canopy, as shown and described.
